DIAPHRAGM AND ASSOCIATED DEVICE

Charles Messick, Brentwood, N. Y.

Application March 11, 1924, Serial No. 698,368
Renewed April 28, 1930

33 Claims. (Cl. 181—32)

This invention pertains to large diaphragms generally. It is a continuation, in part, of my applications Serial No. 383,689, filed May 24, 1920; Serial No. 427,430, filed November 30, 1920; and Serial No. 605,581, filed December 8, 1922.

A broad object of the invention is to provide an improved diaphragm for acoustical or analogous apparatus.

Other objects are to provide improved details of construction for such a diaphragm of large size, and free from troublesome natural periods, efficient, reliable, long wearing, and constant in its performance under varying weather conditions, and also capable of being combined with various well-known diaphragm auxiliaries such, for instance, as the conventional means to vary the tension of a banjo head.

Another broad object is to provide an improved compensating cushion and associated devices for use in connection with the diaphragms of receivers or projectors and transmitters or pickups.

The improved cushion is so designed as to have a tendency to oppose deflection approximately as the square of the amplitude of such deflection, thus compensating for the characteristics of the conventional electro-magnetic apparatus wherein the magnetic pull varies inversely approximately as the square of the air gap separating the armature from the pole pieces.

30 The improved compensating cushion co-acting with a conventional magnetic circuit thus causes vibrations in a diaphragm directly proportional to the variations in current flow instead of in proportion to the magnetic pull.

35 Another object of the compensating cushion and associated devices is to damp natural periods which may be present in the diaphragm and its vibratory load. This damping being a result of the characteristics of the cushion above described and also probably because in a cushion of this type, if there is a natural period at all, such natural period is above the audible range.

Another object of the detailed arrangement of the compensating cushion is to permit the spring to be surrounded by a hollow central pole piece and to thus act along the centre axis of the diaphragm.

Another broad object is to provide improved acoustical performance by combining this improved diaphragm with this improved compensating cushion and/or adjustments, etc.

Another object is to provide an improved folding protecting housing and stand for loud speakers, etc.

Each of these improvements modifies and complements the others and jointly contributes to the improved acoustical performance and efficiency in operation of my invention.

Other objects may appear from the following 5 detail description of the preferred construction and will be pointed out in the claims.

Referring to the drawings:

Fig. 1 is a full size fragmentary plan view of the back of my improved diaphragm showing the 10 arrangement of one of the six groups of wires, etc.

Fig. 2 is a fragmentary substantially true section, taken on the line 2—2 of Fig. 1.

Fig. 2a is a side elevation, twice full size, of 15 one of the twin washers, showing its original bent formation before assembly with the parts, which causes the washers to flatten out, as shown in the other figures.

Figs. 3, 4, 5 and 6 are substantially true sections, twice full size, of the lacing rings and/or dampers taken respectively at said rings or dampers 3, 4, 5 and 6, of Fig. 1, and looking radially toward or from the center of the diaphragm.

20 Fig. 7 is a view diagrammatically explaining the positions and relations of the six groups of wires, one of which appears in Fig. 1.

Fig. 8 is a half size side elevation of an improved folding loud speaker housing for my dia- 30 phragm.

Fig. 9 is a front elevation of the device of Fig. 8.

Fig. 10 is a full size substantially true sectional 35 elevational view, taken on the line 10—10 of Fig. 9.

Fig. 11 is a full size front elevation of the motor mechanism shown in Fig. 10.

Fig. 12 is a back view of the moulded insulation frame of the motor mechanism, shown in 40 Figs. 10 and 11.

Fig. 13 is a back view of the iron core or yoke of Figs. 10 and 11.

Fig. 14 is a plan view of the armature of Fig. 10. 45

The numeral 1 indicates an anchorage ring or frame upon which is cemented, by means of shellac, a sheet of aluminum foil 1/1000 inch thick, indicated by the numeral 100. On top of the foil and fastened through it to ring 1, forty-eight 50 spring steel wires of 10/1000 inch diameter, tensioned approximately to the elastic limit, are provided. These wires are divided into six similar groups, numbered respectively 10, 20, 30, 40, 50 and 60, each group containing eight wires. 55

The wires of each group are anchored at two rows of anchor screws one row near the outer edge of ring 1, and the other row near the inner edge thereof. Half the anchor screws of each row are used for anchoring the ends of wires by compressing the wires beneath twin washers, and the other half for anchorage posts upon which the wires are looped.

In Fig. 7, the positions of the outside row 10 loop anchorages belonging to each group are indicated by narrow enclosures "a", "a", etc., and the position occupied by the end anchorages in each group are indicated by wide enclosures "b", "b", etc.

15 The loop anchorages of the inner row of each group are similarly indicated by "c", "c", etc., and the end anchorages by "d", "d", etc.

The outside wires 31 and 38 of group 30 are also shown in Fig. 7, and all the wires 31, 32, 20 33, 34, 35, 36, 37 and 39 are shown in Fig. 1.

A typical wire 31, of group 30, and its application will be described in detail, all of the forty-eight wires being similar. Wire 31 is looped around anchorage screws 31a1 and 31a2, crossed 25 around aluminum center pin or strut 101, and the ends passed beneath the twin washers 31b1 and 31b2.

A typical twin washer is shown in Fig. 2a, in its original shape before the wires are clamped 30 beneath it. It will be noted in Fig. 2a, that the washer is bent down in the middle to facilitate inserting the wires beneath it at the anchorage screws. When both anchorage screws are tightened the washer flattens out, as shown in the other figures.

Both ends of wire 31 are first subjected to a temporary tension of 2 lbs., or more even up to the elastic limit of the wire, and then clamped in place by the tightening screws 31b3 and 31b4. 40 The tension is thus permanently fixed in that portion of wire 31 extending between the anchorages. The temporary tension is then released in the external end portions of wire 31, shown in dot and dash lines at the left of Fig. 1, 45 which are then broken off. Wires numbered 32, 33, 34, 35, 36, 37 and 38, of group 30, and all the wires of groups 10, 20, 40, 50 and 60, are similarly applied to ring 1.

Referring to Fig. 7, the sequence in which the 50 wires are applied is as follows: First a wire is applied in the outside row of anchorages of group 10, then a wire correspondingly positioned in group 60, then a wire of group 20, then a wire of group 50, then a wire of group 30, for instance, 55 wire 31, then a wire of group 40.

The application of the above wires, one in each 60 of the six groups, produces a symmetrical figure like a substantially flat twenty-four-spoked wheel, and owing to the sequence of the application 65 of the wires the spokes lie nearly in the same plane where one wire crosses an adjacent wire, except for the diameter of one or two wires. This is desirable to facilitate the cementing of the aluminum foil 100 to the wires, as it is more troublesome to apply the cement properly when the adjacent wires lie in widely different planes.

After the application of the above six wires, six 70 more wires are similarly applied at anchorage screws intermediate those to which the first six wires are secured. After the application of the first twelve wires, twelve more are similarly applied at the intermediate anchorages. This completes the application of the twenty-four wires 75 having anchorage near the outer edge of ring 1.

A lacing ring 6, made of 10/1000 inch diameter spring steel wire is then laced between the wires above described and the ends of the lacing ring are wrapped around each other to secure the ring in position. The lacing ring 6 passes under 5 each of the first twelve wires above described and over each of the twelve wires last described, and is shown in Figs. 1, 2 and 6. After lacing ring 6 is completed a spacer tube 102 is slipped over center pin 101.

The reason for providing a row of anchorage screws near the outer edge of ring 1, and a second row near the inner edge, is that screw heads and bodies of adequate diameter cannot be crowded in a single row. The inner row of anchorage screws provides anchorage for twenty-four wires, which is the same number as is provided in the outer row previously described.

Twelve additional wires are crossed over on 20 the top of spacing tube 102 and anchored symmetrically at ring 1. These twelve wires are then laced to wires previously described by means of the lacing ring 5, shown best in Figs. 2 and 5. Thereafter the first-mentioned twenty-four wires 25 below the spacing tube 102 and the lacing ring 6 are laced to the twelve wires above the spacing tube by the lacer 6a, which consists of #30 spool cotton, and is shown in Figs. 2 and 6.

A spacing tube 103 is then slipped over pin 101 until it rests on the twelve wires last applied and 30 twelve more wires are applied on top of tube 103.

The last applied twelve wires are laced to the 35 thirty-six wires previously applied by lacing ring 3, as best shown in Fig. 3, and by cotton lacers 4, 5a and 6b, best shown in Figs. 4, 5 and 6, respectively. The principal object of the lacing rings and lacers is so to truss the whole area of the diaphragm that it will tend to move in synchronism with pin 101.

By shortening or lengthening the unlaced 40 lengths of wires at the flat areas of the diaphragm and varying the relative proportions of the parts, any troublesome natural periods of the diaphragm can be corrected. The diaphragm of the preferred construction is designed with the 45 flat portions, each having a different length of supporting wire between the concentric lacing rings or lacers.

After the parts are assembled, the aluminum 50 foil 100 is cemented to the adjacent portions of all the wires. The wires thus act like the masts of a ship and the foil like the sails.

The attachment between the forty-eight wires and the aluminum foil 100, may be conveniently effected by inverting the diaphragm from the 55 position of Fig. 2, rubbing the foil with a felt pad to make the foil hug the wires and again inverting the diaphragm back into the position of Fig. 2.

A thin coat of lacquer may then be flowed over 60 the foil until it and the adjacent portions of the wires are fully coated. The diaphragm may then be again inverted from the position of Fig. 2 and quickly dried over artificial heat while it is being rubbed with a felt pad to press the foil and 65 the adjacent wires into contact.

Or, with the diaphragm in the position of Fig. 2 70 an upward air pressure may be applied to the foil, and lacquer applied by means of an air brush, to effect the cementing.

Referring to Figs. 1 and 7, it will be noted that 75 holes 104, 104, etc. are provided between each group of wires. These holes are designed to receive through screws for mounting the ring 1 in a loud speaker, or elsewhere, as desired.

Referring to Fig. 1, it will be noted that the anchorage screws are so arranged that the distance between each wire and its nearest neighbor are equal. This symmetry tends to reduce 5 the unsupported area of the foil 100 between the wires 31, 32, etc.

After the diaphragm is formed, as above described, a radially furrowed appearance may be seen looking down upon it, as in Fig. 1. This is 10 due to the use of the felt pad, causing the foil 100 to hug the wires.

In Fig. 2, the rim of a banjo is indicated at 110 in dot and dash lines, over which the diaphragm as a whole may be tightened in the conventional 15 way, if desired, but owing to the stability of the tension of the spring steel wires in my diaphragm, such a tension device is ordinarily superfluous.

In Fig. 2 is also indicated at 120, in dot and dash lines, a fragment of a protective shell, which 20 may be fitted on the back of the diaphragm to protect it from accidental injury. At the front of the diaphragm is also indicated a fragment of the protective grill 130, to protect the front 25 of the diaphragm, and also if desired to support a vibratory motor or generator unit for connection to the diaphragm.

I have observed that the natural period of a wire exceeding about one and one-half inches in 30 undamped length is audible in this diaphragm. Such length therefore is not exceeded in the diaphragm above described.

All of the factors within ring 1 may be varied 35 experimentally in size, proportion, tension, and number when repeated observation makes noticeable a natural period or other defect in performance of the diaphragm. Defects attributable to the motor mechanism, etc. must, however, be corrected before much further refinement of the diaphragm is possible. When a more perfect 40 motor is available, further refinement of the diaphragm can probably be made by varying the factors.

Referring to Fig. 8 and Fig. 9, my loud speaker is shown, including the assembly of ring 1 in a 45 protecting shell 120 and grill 130. The grill 130 is provided with a vibratory electro-magnetic motor or generator 200 at its central portion, and with a leg casting 131, provided with two legs 132 and 133, and fastened to the grill, etc. 50 by screws, as indicated.

The legs 132 and 133 are provided with a folding back leg 134 which folds against the grill 130, as indicated in dot and dash lines, for compactness of packing. In the indicated position, 55 legs 132, 133 and 134 form a stable tripod for the support of my loud speaker.

Shell 120 may be perforated if desired, in order to permit free air to have access to the back of the diaphragm, that is, the surface of the dia- 60 phragm remote from grill 130.

Referring to Fig. 10, the diaphragm is indicated diagrammatically at 70, provided with the ring 1, the perforated protecting shell 120, the grill 130, and the leg casting 131. At the left, a 65 machine screw and nut 1a, secures grill 130, ring 1 and shell 120 together, and at the right a longer machine screw 1b, secures the leg casting 131, the grill 130, the ring 1, and the shell 120 together.

70 It should be noted that ring 1 is provided with a shoulder 1c to center shell 120 and that grill 130 is provided with a shoulder 130a to center the grill with the ring 1.

I have tried several motor units of conventional 75 type for the operation of my diaphragm above

described and have found each type so far tried to exhibit one or more troublesome natural periods. I have therefore designed a special motor unit which I believe will combine with my diaphragm to give superior results. However, I have no 5 reason to think that this improved motor unit would fail to also improve the performance of conventional diaphragms.

The vibratory motor or generator 200 includes a frame of moulded insulation 201 of the shape 10 indicated in Figs. 10, 11, and 12. Frame 201 is attached to grill 130 by machine screws 202, 203 and 204.

A soft iron core 210, which is best shown in 15 Figs. 10 and 13, is provided with an external thread 211, which mates with an internal thread 212 in the moulded insulation 201. The threads are shellacked and screwed together, so that when the shellac hardens these parts become permanently attached to each other. 20

Core 210 is provided with a conventional winding 220 on a spool 221, which is held in place by the friction washer 222.

The upper face, according to Fig. 10, of core 210 is ground flat and a flexible armature 213 25 laid upon it. This armature 213 is loosely held in place by the cap 214 which screws onto the upper end of the external thread 211 of core 210.

Through a slot 215, designed to prevent in- 30ductive losses in core 210, leads 223 and 224 from winding 220, lead through moulded insulation 201, as indicated in Figs. 10 and 12, to binding posts 225 and 226, respectively. These binding posts 225 and 226 are both mounted on 35 moulded insulation 201 and may be suitably connected by a flexible cord 228, so that the motor will operate as a receiver or transmitter.

The center of core 210 is bored and threaded 40 with a buttress thread 230, which engages a threaded plug 231, in such a manner that when the plug is pressed downward according to Fig. 10, considerable friction will be developed at the thread and it will not tend to revolve and get out of adjustment when subjected to vibration. 45 Plug 231 is provided with an adjustable knurled nut 232, which may be locked on the plug by means of the set screw 233.

At the upper end of plug 231, a flat cone 50 pointed cushion 240 is tightly inserted in the recess of plug 231. Cushion 240 may be preferably made of steel wool compressed to the form shown, or cork, felt, rubber, leather like a billiard cue tip, or such elastic material as the 55 associated apparatus with which it is to operate requires. The exact form of cushion 240 is, like the sounding board of a piano, rather the product of an expert workman than the result of exact predetermined design.

Cushion 240 is intended to perform in an im- 60 proved manner the function ordinarily performed by the elasticity in the conventional soft iron diaphragm to retract the diaphragm from the pole pieces. In my case, it serves to 65 retract armature 213 from hollow cylindrical pole piece 216 of core 210.

The air gap between pole piece 216 and arma- 70 ture 213 may be varied by adjusting plug 231 by knurled nut 232. But the knurled nut 232 should be locked on plug 231 in a position to abut core 210 when the maximum required air gap is attained, so as to prevent the excessive bending of armature 213.

Cushion 240 is intended to resist compression 75

- approximately as the square of the distance compressed and thus compensate for the variation of the magnetic pull, which approximately varies inversely as the square of the air gap.
5. The conventional soft iron diaphragm, on the other hand, resists deflection according to Hook's law, or approximately so.

This improved cushion 240 also appears to have a tendency to damp natural periods in the 10 whole vibratory system. The causes of this dampening tendency are probably the very high natural period of the cushion material under compression and cone point of the cushion. In 15 the cone point, the cross section under compression varies as the armature 213 vibrates.

Armature 213 is permanently adjusted in driving contact with pin 101 and thus vibrates the diaphragm 201 when the apparatus is used as a loud speaker, or is vibrated thereby, when 20 the apparatus is used as a pickup. The adjustment of this driving contact may be effected by lengthening or shortening pin 101, or by inserting shims between grill 130 and moulded insulation 201 at the abutting portions.

25. The expression "concave cone" wherever used is intended to mean a formation projecting from the plane of a base which decreases in steepness from the apex toward the base.

I claim:

30. 1. A diaphragm including a stationary frame, highly tensioned vibratory wires anchored at the frame and a sheet of metal attached to the wires where adjacent thereto.

35. 2. An acoustical diaphragm including the combination of a stationary anchorage frame, a vibratory skeleton framework anchored at the frame, and a relatively flexible sheet metal covering mounted upon the framework whereby the diaphragm is rendered imperforate to air.

40. 3. An acoustical diaphragm including the combination of a stationary anchorage frame, a highly tensioned vibratory skeleton framework anchored at the frame, and a sheet metal covering mounted upon the framework whereby the diaphragm is rendered imperforate to air.

45. 4. The combination in an acoustical diaphragm of a rigid frame, a vibratory member mounted therein and including a vibratory framework and a relatively flexible sheet metal member imperforate to air, said vibratory member being tensioned at the rigid frame.

50. 5. The combination of a rigid anchorage frame and a tensioned vibratory member within the frame provided with a central strut and means intermediate the strut and the frame to draw the two external portions of the member together into one plane, a second means intermediate the strut and the first means to deflect the adjacent portions of the member into the general form of a 55 double concave cone with the strut as the apex, whereby the vibratory member may vibrate in phase with any vibratory force applied thereto.

60. 6. A diaphragm provided with a stationary peripheral anchorage frame, a vibratory means therein having a flat outer edge portion and including two members under radial tension and anchored to the frame, means to space the members apart at the centre and means to space the members a predetermined distance from each 65 other intermediate the centre and edge portion.

70. 7. A diaphragm provided with a peripheral anchorage frame, a vibratory means having a flat outer portion, including three members under radial tension to the frame, a compression member at the centre to space the three members

apart; means to hold two of the three members in the one plane a distance from the centre and means at a greater distance from the centre to hold all three members together in the plane of the flat portion.

75. 8. A diaphragm provided with a peripheral anchorage frame, a tensioned vibratory means therein having a flat outer portion adjoining the frame, a shallow conical portion within the flat portion and a steeper conical portion within the 10 shallow conical portion.

9. A diaphragm including a stationary frame, tensioned vibratory wires the ends whereof are anchored at the frame in one general plane, said wires being divided at the centre of the diaphragm 15 into at least two groups spaced apart by a compression member and secured together in said plane by a means between the compression member and the anchorage and a second means between the compression member and the first 20 means to deflect the wires of the two groups toward each other.

10. The combination of an anchorage frame, a vibratory diaphragm within and tensioned to the frame, and a strut at the central portion of the 25 diaphragm having more than two shoulders for holding several portions of the diaphragm away from the general plane thereof at different levels, and portions of the diaphragm held at each of said levels.

30. 11. The combination of a frame, a vibratory diaphragm therein including means capable of sustaining tension and imperforate to air, radially tensioned and attached at its outer edge to an anchorage portion of the frame, and central 35 means to deflect the first mentioned means out of the plane of the anchorage portion into substantially the shape of a concave cone including most of the area of the diaphragm and assuming an increasingly flat form as the anchorage portion 40 is approached.

12. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a 45 straight line having one end at said point and passing through and following the contour of the periphery of the membrane, and means for applying sound reproducing vibrations to said membrane.

50. 13. A sound reproducer of the character described, comprising, in combination, a supporting frame, a vibratory membrane fastened to said frame, resilient means maintaining said membrane under tension along lines converging inward 60 of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means including a vibratory member to which said membrane is connected.

65. 14. A sound reproducer of the character described, comprising, in combination, a supporting frame, a vibratory membrane mounted in association with said frame, resilient means maintaining said membrane under tension along lines 70

75

30

35

75

converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means being adjustable whereby the tension on the membrane may be varied.

15. The combination of a frame, an acoustical diaphragm therein including a surface extending at its outer edge to the frame, provided with a larger amount of material per unit area at a central portion, and yielding means to deflect said portion into substantially the shape of a concave cone.

16. The combination in an acoustical diaphragm of a peripheral stretching frame, a vibratory portion within the frame, said vibratory portion being provided with radiating wires attached at the frame, and a membrane supported by said wires.

25. 17. The combination of a frame provided with a hole, a tensioned member covering the hole, provided with a projecting central portion, a flatter portion surrounding said projecting portion, and tensioned metallic means anchored at the frame in intimate contact with and supporting the flatter portion of said membrane.

18. The combination of a frame provided with a hole, a tensioned membrane covering the hole, provided with a projecting central portion, and a flatter portion near the frame, tensioned supporting means for said flatter portion and anchorage members for said means passing through the edge of said membrane and into said frame.

19. A device as in claim 12 wherein the membrane is of metal, whereby it is substantially free from expansion and contraction due to changes in atmospheric humidity.

20. In combination, a flexible membrane diaphragm, a support for the periphery of said diaphragm, means for tensioning said diaphragm and for fastening said diaphragm to said support and driving means for said diaphragm positioned to engage a portion thereof which is not in the plane through the peripheral portion of the diaphragm, the peripheral portion of said diaphragm having substantially a plane surface and the central portion of said diaphragm having substantially the shape of a cone.

21. The combination of a frame, a tensioned diaphragm of loud speaking area, substantially in the shape of a concave cone, an electric motor provided with an armature in driving relation to the diaphragm, substantially at the apex of the cone and elastic means to stress the diaphragm through the armature.

22. A sound reproducer of loud speaking area and of the character described, comprising, in combination, a supporting frame, a vibratory membrane fastened to said frame, resilient means maintaining said membrane under tension along lines converging inward of its periphery and toward a point located outside of the general plane of the periphery, said membrane being strengthened around said point, whereby the material of which it is made will be more effectively disposed to resist said resilient means, said membrane as so tensioned having substantially all parts thereof within a surface generated by a straight line having one end at said point and passing through and following the contour of the periphery of the

membrane, and means for applying sound reproducing vibrations to said membrane.

23. A device as in claim 22 in which there are several separate means for strengthening the membrane at the point, which extends radially therefrom.

24. An acoustical diaphragm comprising, in combination, a stationary peripheral frame, a vibratory portion within the frame, having a stiff, substantially concave conical portion and a relatively flexible edge, said conical portion including means to substantially define the shape of the central portion of said conical portion and a surface means covering said defining means and designed to cooperate and move as a unit therewith.

25. An acoustical diaphragm comprising in combination, a stationary peripheral frame, a vibratory portion within the frame and radially tensioned thereto, having a stiff substantially concave conical portion and a relatively flexible edge, said conical portion including means to substantially define the shape of the central portion of said conical portion and a surface means covering said defining means and designed to cooperate and move as a unit therewith.

26. An acoustical diaphragm comprising in combination, a stationary peripheral frame, a vibratory portion within the frame and radially tensioned thereto, having a stiff, substantially concave conical portion and a relatively flexible edge, said conical portion including means containing more material per unit area to substantially define the shape of the central portion of said conical portion and a surface means covering said defining means and designed to cooperate and move as a unit therewith.

27. A loud speaker provided with a diaphragm of direct acting area, having a substantially conical central portion and a stationary motor mounted substantially in line with the axis of the conical portion, said motor being provided with a movable actuating and damping means in actuating and damping relation to said conical portion, whereby excessive movement of the diaphragm, at resonance, is appreciably damped.

28. A device as in claim 15 in which the larger amount of material per unit area at the central portion consists of close together radial means, separated from each other at a distance from the central portion.

29. The combination of a frame, a vibratory diaphragm of direct acting area therein, extending from a centre and tensioned to said frame, concentric sections of said diaphragm being of greater average thickness near the centre than remote therefrom, said diaphragm including many tension means radiating from the centre and separated from each other where remote therefrom, and elastic means to deflect the diaphragm into substantially the shape of a concave cone.

30. A diaphragm including the combination of a stationary peripheral frame, a first means, substantially imperforate to air, of loud speaking area and enclosed in the frame, deflecting means connected to the first means whereby it is tensioned substantially into the shape of a concave cone, gradually increasing in steepness toward the centre, said first means being so designed that the apex of the cone contains more material under tension per unit area than the outer portion thereof, whereby vibrations applied at the apex may be effectively distributed.

31. The combination of a stationary peripheral frame, a diaphragm within the frame in the general form of a cone of increasing steepness as its centre is approached, actuation attachment means at the apex of the cone and adjustable tensioning means for the edge portion of the diaphragm.

32. The combination of a frame, an acoustical diaphragm therein of large and direct acting area, including a surface extending at its outer edge to the frame, yielding means to deflect a central portion thereof into substantially the shape of a concave cone having a steeper apex than edge portions; said diaphragm being pro-

vided with several radial, tension means, extending from the apex toward the frame.

33. A loud speaker provided with a diaphragm of direct acting area, having a substantially conical central portion and a stationary motor mounted substantially in line with the axis of the conical portion, said motor being provided with a field member free from any independent field windings, and movable actuating and damping means in actuating and damping relation to said conical portion, whereby excessive movement of the diaphragm, at resonance, is appreciably damped. 5 10

CHARLES MESSICK.
